UNITED STATES PATENT OFFICE.

ROBERT GORTON, OF BROOKLINE, MASSACHUSETTS; CHARLES W. NOYES ADMINISTRATOR OF SAID ROBERT GORTON, DECEASED.

GARTER.

1,351,567.

Specification of Letters Patent. Patented Aug. 31, 1920.

Application filed October 7, 1919. Serial No. 329,072.

To all whom it may concern:

Be it known that I, ROBERT GORTON, a citizen of the United States, residing in Brookline, in the county of Norfolk and State of Massachusetts, have invented certain new and useful Improvements in Garters, of which the following is a specification.

This invention relates to gentlemen's garters of the class in which the stocking-engaging clasp members are connected with the ends of the leg-band by clasp suspending devices secured to a pad arranged between the ends of the leg-band. This kind of garter is commonly called a pad garter.

In my United States Patents Nos. 1,325,716 and 1,325,717 of Dec. 23, 1919, I have shown, described, and claimed a garter and a method of making it, in which the garter is made from strip material folded in such manner as to provide a pad and connected leg-band parts extending in opposite directions from the pad. As shown in said patents, the strip material is of uniform width, but according to my present invention the pad and the connected leg-band parts are made from a blank in which the middle part is somewhat wider than the end portions. In this way, pads of comparatively large size may be provided and may be better reinforced, while the leg-band parts, which are narrower, are better adapted to connect with other portions of the leg-band.

In the accompanying drawings:

Figure 1 is a perspective view of a garter, embodying my improvements.

Fig. 2 illustrates a strip or length of material containing a plurality of blanks.

Fig. 3 shows how the separate blanks are cut from the strip shown in Fig. 2.

Fig. 4 indicates how a blank is folded upon itself and stitched to form a closed or loop portion and free ends.

Fig. 5 shows how the loop portion is spread or opened.

Fig. 6 illustrates the next step, which consists in flattening the loop.

Fig. 7 shows how the free ends of the blank are turned down upon the flattened loop portion.

Fig. 8 is a front view of the blank folded in the manner indicated in Fig. 7.

Fig. 9 shows the folded blank associated with a clasp.

Fig. 10 shows the manner of stitching the

blank to secure the folds and attach the clasp.

Fig. 11 is a perspective view of a complete garter with my improvements applied and indicates how the pad and connected leg-band parts are associated with the remainder of the leg-band.

Fig. 12 shows a blank of suitable shape for forming a pad and connected leg-band parts.

Fig. 13 shows how the blank illustrated in Fig. 12 is folded and how the folds may be secured together by diagonal lines of stitches set at different angles to provide pads of various widths.

Fig. 14 illustrates diagrammatically how pads of various widths may be formed from the folded blank shown in Fig. 13.

Fig. 15 shows another form of blank which may be used.

Fig. 16 illustrates still another shape of the blank.

Fig. 17 shows a longitudinal section on the line 17—17 of Fig. 15.

In Fig. 1, A indicates the pad, B a portion of the leg-band, and C, C' leg-band parts projecting from the pad, one of which C is permanently connected with the part B, and the other C' is detachably connected therewith by fastening devices D of usual construction. A clasp E is connected to the pad by a suspending device F, and the leg-band is equipped with a slide or take-up G applied in the usual way.

In general construction, the garter is similar to those shown in my before mentioned patents, but the shape of the blank is different, provision being made for providing a comparatively large pad.

The blank from which the pad and its two connected leg-band parts are made is somewhat wider in its middle portion than in its end portions. Such blanks may be cut from suitable material by dies, or a series of connected blanks may be formed by a suitable machine in strip form, as indicated in Fig. 2. Such a strip may be tubular and may be easily divided into separate blanks in the manner indicated in Fig. 3.

In order to form a pad and connected leg-band parts from such a blank, it is folded upon itself in the manner indicated in Fig. 4 and the folds are secured together by stitches a, preferably arranged diagonally to provide a closed loop portion a' and free

end portions a^2 . The part a' provides material for the pad, while the parts a^2 provide material for the connected leg-band parts. The loop portion of the blank is then 5 opened in the manner indicated in Fig. 5, and then flattened as indicated in Fig. 6, and then the parts a^2 are turned and pressed down upon the part a' . These operations are similar to those described in my applications before mentioned.

Fig. 8 shows in front elevation the pad and its connected leg-band parts when folded and pressed together in the manner indicated in Fig. 7.

15 Fig. 9 shows how a clasp is applied to the pad before the folds of the latter are stitched, and Fig. 10 indicates at α the various lines of stitching which secure the folds of the pad to each other and to the leg-band parts and also attach the suspending device F of the clasp E to the pad.

The pad and its leg-band parts thus constructed may be connected with the part B of the leg-band in the manner indicated in 25 Fig. 11, the end b of the part B being secured to the outer portion of the part C.

When the pad and its connected leg-band parts are made of tubular material, the end b of the leg-band may be inserted in the 30 open end of the part C and secured thereto in the usual way. The part C' carries one member of the catch or cast-off which cooperates with the other member carried by the leg-band part B.

35 It will be observed that the blank from which the pad and the connected leg-band parts are made is wider at the middle than at its ends. In this way a relatively large pad is made and yet the outer ends of the leg-band parts may be readily connected with the remainder of the leg-band, the outer ends of the parts C, C' being preferably 40 of substantially the same width as that of the part B.

45 It will also be noted that when a blank of the form shown in Fig. 3 is employed, the reinforcing parts or rear portions of the pad are of comparatively large size as compared with the corresponding parts where the pad and leg-band parts are made of a strip of material of uniform width. In this way the 50 strength and stiffness of the pad is increased.

It will, of course, be understood that where desirable several layers of material may be 55 used in the blank and the pad may be faced or lined in any usual way. Ordinarily this is not required or necessary.

The shape of the blank employed is such as 60 to increase the size of the pad in a vertical direction; the width of the pad horizontally may be varied in the manner indicated in Fig. 13 by varying the inclination of the line of stitches which secure together the folds

of the blank. Thus when the stitches are disposed at 1, Fig. 13, a pad of the size shown 65 at 1 in Fig. 14 may be made. When the stitches are disposed as indicated at 2, Fig. 13, the pad will be of the width indicated at 2 in Fig. 14, and when the stitches are inclined in the manner indicated at 3, Fig. 13, 70 the pad will have the shape indicated at 3, Fig. 14.

The blank may be of the form shown in Fig. 12, *i. e.*, expanded or widened at top and bottom, or it may be of the form shown in 75 Fig. 16, expanded or widened on one side only, *i. e.*, either at top or bottom, but preferably a blank of the kind shown in Fig. 12 is employed.

The blank may be made entirely of material of a single thickness of solid or non-tubular material, or it may be made from tubular material or material of double thickness and it may be reinforced if desired.

Another way of making the blank is illustrated in Figs. 15 and 17. In this case the middle or body portion m of the blank is made of solid, *i. e.*, non-tubular material, while the end portions m' are tubular. Blanks of this kind can be readily made by 80 machinery. If preferred, one end only of the blank may be made in tubular form, this end being adapted to receive and neatly connect with one end of the leg-band.

85 It will be understood that my present invention relates to a garter in which the pad and connected leg-band parts are made from a blank which is wider in its middle portion than at its ends, the method of folding the blank producing the garter and the construction of the garter independently of this expanded form of blank being claimed in my patents before mentioned.

90 I claim as my invention:

1. In a garter, a pad and leg-band parts 105 formed from a single piece of material which is wider in its middle portion than at its ends and which is folded and secured to provide a pad reinforced at the back by folded portions of the blank, and parts extending upward and outward in opposite directions from the rear of the pad to provide portions of the leg-band.

2. In a garter, a pad and connected leg-band parts, the pad consisting of a front 115 part and integral reinforcing rear parts of solid or flat material, the leg-band parts being connected to each other by a vertically disposed seam forming their line of junction with the rear parts of the pad, and at least one of the leg-band parts at its outer end having a tubular portion adapted to connect with one end of a leg-band.

120 In testimony whereof, I have hereunto subscribed my name.

ROBERT GORTON.
